CONSOLE FOR TEACHING ARITHMETICS

Donald Charles Stephan, Poway, and George William Cone, La Jolla, Calif., assignors to Eric F. Burtis, Redwood City, Calif.

Filed Oct. 25, 1974, Ser. No. 517,987

Term of patent 14 years

Int. Cl. D19—07

U.S. Cl. D19—62

FIG. 2

FIG. 3

FIG. 4

FIG. 5

FIG. 1 is a perspective front view of a console for teaching arithmetics showing our new design with open cover;

FIG. 2 is a side elevational view thereof with closed cover;

FIG. 3 is a rear elevational view thereof with closed cover;

FIG. 4 is a top plan view thereof with closed cover; and

FIG. 5 is a bottom plan view thereof with closed cover.

We claim:

The ornamental design for a console for teaching arithmetics, as shown and described.
